His Attorney.

UNITED STATES PATENT OFFICE.

RALPH H. CHADWICK, OF FORT WAYNE, INDIANA, ASSIGNOR TO GENERAL ELECTRIC COMPANY, A CORPORATION OF NEW YORK.

STATIONARY INDUCTION APPARATUS.

1,315,815.

Specification of Letters Patent. Patented Sept. 9, 1919.

Application filed February 8, 1919. Serial No. 275,461.

To all whom it may concern:

Be it known that I, RALPH H. CHADWICK, a citizen of the United States, residing at Fort Wayne, in the county of Allen and 5 State of Indiana, have invented certain new and useful Improvements in Stationary Induction Apparatus, of which the following is a specification.

My invention relates to stationary induction apparatus and has for its object an improved construction therefor whereby a stronger device electrically is produced in a more economical fashion than was heretofore known.

15 More specifically my invention relates to the construction and insulation of windings in transformers, some reactances and the like, and has for its object an arrangement of parts which will provide desired insulation characteristics where insulating media having different permittivities are employed between the various groups of windings.

It is now known that the surface of contact between two insulating media generally 25 has less dielectric strength to resist creepage discharge thereover than the strength of either of the media taken alone; for instance, it is known in transformer construction that a discharge will take place between a coil 30 of the high voltage winding and a coil of the low voltage winding at a much lower voltage, if there is a surface of some solid insulation between the windings in the oil or other insulating fluid surrounding them 35 which may be followed, than where no such surface exists as when the intervening dielectric is either wholly oil or else solid material.

The use of both solid and fluid insulating 40 materials together in the construction of the type of electrical apparatus to which my invention applies is rendered necessary in order to provide both for their windings being mechanically supported in a rigid 45 manner and for the adequate cooling and ventilation of their windings. The disadvantages incident to this low dielectric strength for resisting creepage over the surface of contact of two dielectric media may 50 be overcome, however, if this path is made sufficiently long to require a higher voltage to effect a discharge over the surface than through the dielectric.

In the practice of my invention I have 55 thus overcome this difficulty in a cheap and

efficacious manner by a novel arrangement of the solid insulating material between the windings which provides an extended leakage path having the requisite resistance of creepage. To this end I insert individual 60 slabs of solid insulating material, symmetrically placed with respect to each other, and arranged to bear tangentially against one winding and at the same time to furnish support at their respective edges for another 65 winding. The use of individual insulating slabs not only avoids the creepage difficulties inherent in the use of solid dielectric material between windings, but also affords a convenient means for assembling the coils 70 rigidly in a desired spaced relation without any other instrumentality, such as wedges; since the final slab of a given group may be sprung into place. As a further advantage, the use of individual insulating slabs permit 75 coils of varying interior diameters to be rigidly supported in a simple manner without a complicated barrier construction.

For a more complete understanding of the nature and objects of my invention reference should be had to the following detailed description taken in connection with the accompanying drawing in which:

Figure 1 is a view partly in section and partly in elevation of a construction for 85 transformer embodying my invention; a portion of the core construction being disassembled for the sake of clearness in the illustration. Fig. 2 is a plan view of the construction illustrated in Fig. 1. Fig. 3 90 is a perspective view of an assembled transformer embodying my invention. And Fig. 4 is a perspective view showing details of one form of insulating slab employed in 95 my invention.

In the illustration of the application of my invention I have chosen a distributed core transformer because it is to the manufacture of such apparatus that I contemplate the most extended application, although obviously it is not so limited in its application. 100 but may be applied to any type of stationary induction apparatus in which the problem of insulating against creepage arises.

Referring now to the drawings, 10 represents the central leg of a distributed core, and 11 represents the bottom yoke members radiating from the base of leg 10; the completed core being shown in Fig. 3.

These yoke members 11 support an insu- 110

lating collar 12, which in turn supports the spacing elements 13; the latter being used to insure the proper spacing of the lowermost coil 14 of the high voltage windings 5 15 from the core.

The high voltage winding, in the instance illustrated, is designed to have one terminal grounded. As a consequence it is not necessary to have those coils adjacent the 10 grounded terminal spaced as far from the core as those coils adjacent the line terminal. Coil 14 is spaced from the core sufficiently to be connected to the line lead. The other coils of winding 15 have a series of increasing lateral dimensions so that the last coils 16, the potential whose end turns differ only slightly from ground potential, are relatively nearer the core at all points than the coil 14.

20 The coils of the winding 15 also have the customary insulating barriers 17 inserted between each other and also at the ends of the stack.

The low voltage winding 18 is shown as 25 a cylindrical winding which is spaced from the central leg 10 of the core the insulating cylinder 19, but obviously this low voltage winding can be made in any desired or approved form. The winding 18 is situated 30 within and concentrically with the winding 15 and has an exterior insulating cylinder 20 surrounding it to reinforce the insulating jacket customarily formed about windings.

In order to insure the proper spacing of 35 the coils of winding 15 from the coils of winding 18 and at the same time to provide an extended leakage path along the surface of contact between the dielectric media between the windings, I employ insulating 40 slabs 21, here shown as four in number, symmetrically placed in order to prevent the windings becoming eccentrically disposed with respect to each other.

These slabs 21 are made sufficiently thick 45 to yield a substantially rigid construction when assembled and are so situated that their axial central portion bears tangentially against the cylinder 20, while their edges 22 are formed to bear against and retain the 50 coils of the winding 15 in proper spaced relation with respect to the winding 18.

Where the exterior winding coils are of varying diameters, as those of the high voltage winding 15, it is necessary that the insulating slabs 21 be given a stepped formation along their supporting edges; the steps on the edge 22 of the slab 21 being indicated at 22' and 22''. The widest portion of the slab 21 thus supports the coils of 55 greatest potential above ground, as the coil 14, so that these coils have the longest surface creepage path to the winding 18. That portion of the slab 21 between steps 22' and 22'' accordingly supports the intermediate coils of the high voltage winding 60.

while the narrowest portion of the slab supports those coils nearest ground potential, as the coil 17; thus providing a creepage path whose length varies with the voltage to be withstood.

The disposition of the tangential spacers or slabs 21, which I have described, provides a sufficiently long creepage path from a point on a coil in the high voltage winding to a point on the low voltage winding 18 75 which path traverses the surface of the slab 21 from its edge to the center to require a greater voltage for effecting discharge along this path than the puncture voltage of the dielectric media employed.

This construction I have found particularly advantageous for transformers designed to furnish a constant operating source of difference of potential across the electrodes of X-ray tubes, such for instance 85 as are described in U. S. Letters Patent to Coolidge No. 1,203,495 issued October 31, 1916; since such duty requires a transformer which shall be insulated against the relatively large difference of potential, which 90 occurs across the terminals of the high voltage windings, without undue bulk or weight in the transformer itself.

Having now described what is at present the best means known to me for carrying 95 out an embodiment of my invention, I would have it understood that such means are merely illustrative and that I do not mean to be limited thereby to the exact details shown nor in the choice of recognized 100 equivalents except as defined in my claims hereunto appended.

What I claim as new and desire to secure by Letters Patent of the United States, is:

1. In electrical apparatus, the combination with concentric windings, of individual spacers disposed between the windings, placed tangentially against one winding and having their respective edges supporting another winding.

2. In electrical apparatus, the combination with concentric windings, of a core supporting the windings, and individual spacing elements placed tangentially against the inner winding and having their respective edges bearing against the outer winding.

3. In electrical apparatus, the combination with concentric windings, comprising an inner group and an outer group, of individual insulating spacers placed tangentially against the inner group and having their respective edges formed to bear against the outer group.

4. In electrical apparatus, the combination with concentric windings, comprising inner and outer groups, said outer group being composed of coils, of a core, and individual insulating spacing elements symmetrically disposed between the inner and outer groups, placed tangentially of the in-

ner group and having their respective edges formed to bear against the individual coils of the outer group.

5. In electrical apparatus, the combination with concentric windings, comprising inner and outer groups, said outer group being composed of coils of varying diameters, of a core supporting the windings, and individual insulating spacing elements symmetrically disposed between the inner and outer groups, placed tangentially of the inner group and having their respective edges formed in steps to bear against the inner surfaces of each of the coils of the outer group.
6. In electrical apparatus, the combination with windings supporting each other in definite spaced relations, of a plurality of different insulating media intervening between said windings, one of which comprises solid individual spacing devices for said windings; said devices being formed to extend diagonally between the windings thereby affording a longer creepage path between the windings over said devices than any direct puncture path.

7. In electrical apparatus, the combination with a core, of concentric high voltage and low voltage windings mounted thereon, said high voltage winding comprising coils

of varying diameters arranged so that their distance from said core is proportional to their respective potential elevations above ground, and insulating slabs placed tangentially of the low voltage winding, having their edge supporting the high voltage coils and formed to provide a creepage path whose length varies as the potential elevation of the coil supported.

8. In electrical apparatus, the combination with a distributed core, of concentric high voltage and low voltage windings mounted on the central leg thereof and adapted to be surrounded by a fluid dielectric medium said high voltage winding comprising coils of varying diameters arranged so that their distance from said leg is proportional to their respective potential elevations above ground, and insulating slabs immersed in said medium between said windings, placed obliquely between said windings but engaging with each other for holding said windings in predetermined spaced relations whereby a longer creepage path is provided over the surface of said slab than any direct puncture path between said windings.

In witness whereof, I have hereunto set my hand this 30th day of January, 1919.

RALPH H. CHADWICK.
